UNITED STATES PATENT OFFICE.

WILLIAM M. GENTLE, OF GREENWOOD, INDIANA.

GAME APPARATUS.

970,489.

Specification of Letters Patent. Patented Sept. 20, 1910.

Application filed June 10, 1909. Serial No. 501,408.

To all whom it may concern:

Be it known that I, WILLIAM M. GENTLE, of Greenwood, county of Johnson, and State of Indiana, have invented a certain new and useful Game Apparatus; and I do hereby declare that the following is a full, clear, and exact description thereof, reference being had to the accompanying drawings, in which like letters refer to like parts.

The object of this invention is to improve the construction of game apparatus similar to bowling alleys, excepting that the alley pins are pivotally mounted or otherwise fixed instead of being separable and removable.

The chief feature of this invention consists in mounting the alley pins in place by means situated below the upper surface of the ball course, so that above the ball course nothing will appear excepting the alley pins, and they will have the same appearance as in bowling alleys, and are preferably located in the same way. To that end a means is provided that extends downwardly from the lower end of each alley pin through a slot or like opening in the ball course, and is fulcrumed or pivoted on means below the ball course, so that when the pin is knocked down by a ball, the pin will swing below the ball course and be out of the way as much so as in ordinary bowling alleys. There is also a resetting means mounted below the ball course for returning the alley pins to their normal position.

Another feature of the invention consists in connecting the means for holding and controlling the various alley pins, so that when a certain alley pin is knocked down by a ball, it will throw certain other alley pins and thus produce the same result and effect the same score as is usually the case in the ordinary bowling alley.

The nature of the invention will be understood from the accompanying drawings and the following description and claims.

In the drawings Figure 1 is a side elevation of the game apparatus centrally broken away. Fig. 2 is a bottom view of the rear portion of the ball course and alley pin controlling means, viewed from the line 2-2 of Fig. 1, and parts being broken away. Fig. 3 is a section on the line 3-3 of Fig. 1 show-

ing the alley pins elevated. Fig. 4 is a plan view of a rear portion of the device, other parts being broken away, and the 55 alley pins being all upright. Fig. 5 is a longitudinal vertical section through a portion of the device showing the means for mounting an alley pin in the two positions thereof, parts being broken away. Fig. 6 60 is a horizontal section on the line 7-7 of Fig. 5. Fig. 7 is a cross section on the line 8-8 of Fig. 5, showing an upright alley pin in elevation. Fig. 8 is a section on the line 9-9 of Fig. 5. Figs. 9, 10, 11 and 12 65 are diagrams of the positions of the alley pins in the course of a game and the connections between the alley pins, whereby when a certain alley pin is struck, other alley pins will be also thrown. The blacks 70 are pins which have been thrown down and the whites are pins not struck.

The device herein shown has a ball course 15 with a trough 16 at each side thereof, as is common in bowling alleys, said ball course 75 being mounted upon the supports 17 intermediate of its ends, and connected with the back portion 18 at the rear and with a post 19 at the front. There is also a return ball trough 20 for the balls 21. A resetting lever 80 22 is pivoted at 23 and connected with the pivotally connecting rod 24 extending rearward to the lever 25 fulcrumed at 26 intermediate of its ends to the bracket 27 extending down from the ball course. 85

The alley pins 30 are preferably of the same shape and number as bowling alley pins, and are mounted on the rear portion of the ball course at the forward end of disappearing slots 31 in the ball course, 90 through which the alley pins disappear when struck. Each alley pin 30 is secured at its lower end rigidly to an arm 33, fulcrumed between its ends on a rock shaft 34, which extends horizontally through the device and is mounted in the side boards 36. Said alley pin arm 33, as seen in Fig. 9, operates between a pair of parallel plates 37 secured by the bolts 138 to the underside of the ball course and the rock shafts 34 extending through said plates. These plates 100 extend forwardly of the rock shaft 34 and furnish a suitable guide for the lower end of the arm 33, so that said plates 37 act as

on the lower part of the arm 33 hold the alley pin from lateral play or movement and also assist in holding it firmly in its upright position and guide said arm during the oscillation thereof. A pin 38 is secured to and extends through the lower end of the arm 33 and projects and operates through slots 39 in the plates 37 that are curved concentrically with the rock shaft 34. This 10 also helps in guiding and holding the alley pin. The arms 33 are loosely mounted on said rock shaft 34, so that when the alley pins are struck, they will not turn the rock shaft 34.

15 The alley pins are reset by the following means: On each rock shaft 34 there are a pair of arms 40 rigidly secured, one on each side of the pair of plates 37 that are oscillated when said shaft is oscillated and move 20 along the surface of the plates 37. When an alley pin is struck, it will be knocked down through the ball course into the dotted line position shown in Fig. 5, and the lower end of the arm 33 will be thrown forwardly, 25 so that the pins 38 will rest at the forward upward end of the slots 39 and in position to be engaged by the resetting arms 40 when they are oscillated from the full-line position shown in Fig. 5 to the dotted-line position. 30 That movement of said arms 40 will return the alley pins from the horizontal to the vertical position. Then said arms 40 and the rock shaft 34 are returned to their original position. The rock shafts 34 are 35 simultaneously given the resetting movement by the means shown in Fig. 1. There is a bell crank lever 41 secured on the outer end of shaft 34 rigidly. One of its arms is slotted to receive a pin 42 that extends 40 through a slot in the upper end of the lever 25. The upper ends of the levers 41 are connected by a bar 43, whereby all the shafts 34 will be simultaneously given the resetting movement. To facilitate the resetting 45 movement a spring 44 is secured between the plates 37 at the point 45, and near its point of attachment bears against the pin 46, so that the free end of the spring is in position to be engaged by the lower end of the arm 50 33 as the alley pin is moving downwardly after being struck from its vertical to its horizontal position. This breaks the force 55 of the movement of the alley pins in the latter part of its downward forward movement, and the spring is upward as shown in the dotted-line position shown in Fig. 6. Consequently, when the resetting lever 22 is 60 actuated at the forward end of the alley, thus causing the resetting movement of the shafts 40, all the springs 44, which have been moved to the rearward position, will assist to return the arms 33 and the alley pins to the upright position. Hence the spring 44 serves as a substitute for a buffer construc-

tion to break the force of the blow of the 65 falling alley pin.

In order that a ball which strikes a certain alley pin will cause the overthrow of substantially the same alley pins and the same number of alley pins as it would in 70 ordinary bowling, cables 70 are connected with the corresponding ends of the pins 38 in the arms 33 of all the alley pins in an oblique row. Since the oblique rows are in two directions, the cables cross each other 75 substantially as shown in Fig. 2, but they are not connected with each other. The operation of this part of the device is illustrated in Figs. 2 to 12. In Fig. 12 all the pins are standing excepting one and it has been 80 knocked down, and when that pin was knocked down it did not pull or throw any other pin, it being the rear pin at one side. If the second pin from the rear at either 85 side is struck, the cables connecting it with the two pins to the rear thereof will also cause their overthrow, as indicated in Fig. 11. If the third alley pin from the rear is struck, it will cause all the alley pins to the 90 rear thereof in the diagonal rows connected with such alley pin, and also the alley pin directly in the rear of said struck alley pin to be thrown, as indicated in Fig. 10. If the front alley pin is struck, it will cause the overthrow of all the others, as indicated 95 in Fig. 9, since it throws all the pins at the sides of the series and they throw the intermediate ones.

What I claim as my invention and desire to secure by Letters Patent is:

1. A game apparatus including a ball course, alley pins, and means below the upper surface of the ball course and connected with the lower end of each alley pin for pivotally mounting it, so that when struck 100 105 the alley pin may move to a position below the level of the ball course.

2. A game apparatus including a ball course provided with slots through which the alley pins may disappear when struck, 110 115 alley pins, and means below the surface of the ball course for pivotally mounting each alley pin.

3. A game apparatus including a ball course provided with slots through which the alley pins may disappear when struck, 120 125 alley pins, and means connected with the lower end of each alley pin and extending through one of said slots and pivotally mounted below the upper surface of said ball course.

4. A game apparatus including a ball course provided with slots through which the alley pins may disappear when struck, 130 135 alley pins arranged in transverse rows, a rod extending transversely of the device beneath the ball course, and means connected with the lower end of each alley pin and

extending through a slot in the ball course and pivoted on said rod.

5. A game apparatus including a ball course, alley pins, means below the upper 5 surface of the ball course and connected with the lower end of each alley pin for pivotally mounting it, so that when struck the alley pin will move to a position below the level of the ball course, and means for 10 returning the alley pins to their normal upright positions.

6. A game apparatus including a ball course provided with slots through which the alley pins may disappear when struck, 15 alley pins, an arm secured to the lower end of each alley pin and extending downwardly through a slot in the ball course, means for pivoting said arm between its ends, and means for actuating the lower 20 end of said arm for returning the alley pin to its normal upright position after it has been thrown down.

7. A game apparatus including a ball course provided with slots through which 25 the alley pins may disappear when struck, alley pins, an arm secured to the lower end of each alley pin and extending downwardly through a slot in the ball course, means for pivoting said arm between its 30 ends, guides extending downwardly from the ball course beside said arm for guiding the same in its oscillations, and means for actuating the lower end of the arm for returning the alley pin to its upright position.

35. 8. A game apparatus including a ball course provided with slots through which the alley pins may disappear when struck, alley pins, an arm secured to the lower end of each alley pin and extending downwardly 40 through a slot in the ball course, means for engaging said arm for limiting its movement when the alley pin is struck by a ball, means for pivoting said arm between its ends, and means for actuating the lower end 45 of said arm for returning the alley pin after it has been thrown down to its normal upright position.

9. A game apparatus including a ball course provided with slots through which 50 the alley pins may disappear when struck, alley pins, an arm secured to the lower end of each alley pin and extending downwardly through a slot in the ball course, a horizontal rock shaft mounted below the ball course and upon which said arm is fulcrumed between its ends, a pair of guide plates extending down from the ball course, one on each side of said arm and having curved slots in them concentric with the 55 rock shaft, a pin extending through the lower end of said arm that projects through said slots, a resetting arm secured on said rock shaft at each side of said guide plates adapted to engage said arm pin when said

alley pin is in its downward position, and means for operating the rock shaft for resetting the alley pin.

10. A game apparatus including a ball course provided with slots through which the alley pins may disappear when struck, 70 alley pins, an arm secured to the lower end of each alley pin and extending downwardly through a slot in the ball course, a horizontal rock shaft mounted below the ball course and upon which said arm is fulcrumed between its ends, a pair of guide plates extending down from the ball course, one on each side of said arm and having curved slots in them concentric with the rock shaft, a pin 75 extending through the lower end of said arm that projects through said slots, a resetting arm secured on said rock shaft at each side of said guide plates adapted to engage said arm pin when said alley pin is in its downward position, means for operating the rock shaft for resetting the alley pin, and a spring secured to one of said guide plates in position to be engaged by said arm pin when the alley pin is thrown downwardly and brought under tension so as to 80 assist in returning the alley pin to its upright position.

11. A game apparatus including a ball course provided with slots through which the alley pins may disappear when struck, 95 alley pins arranged in transverse rows, an arm secured to the lower end of each alley pin, a rock shaft under each transverse row of alley pins and upon which all the arms from the alley pins in a transverse row are 100 fulcrumed between their ends, a resetting arm secured on each rock shaft in position to engage the lower part of said alley pin arm when the alley pin is in its downward position, and means for operating all of the 105 rock shafts, whereby all the alley pins will be simultaneously returned to their upright positions.

12. A game apparatus including a ball course, alley pins, means for pivotally 110 mounting each of said alley pins in position to be struck by a ball moving over said course, and means for enabling one of said alley pins when struck to throw down other of said alley pins.

115. 13. A game apparatus including a ball course, alley pins, means below the upper surface of the ball course and connected at the lower end of each alley pin for pivotally mounting it, so that when struck the alley 120 pin will move to a position below the level of the ball course, and a connection between the pivoting parts of said alley pins, whereby when one alley pin is struck said connection will throw other alley pins down.

125. 14. A game apparatus including a ball course with slots therein through which alley pins may disappear, alley pins, means se-

cured to the lower end of each alley pin that extends through said slot and is pivotally mounted below the ball course, and a cable connecting the pivoting means of certain 6 alley pins, whereby when one alley pin is struck it will operate said connection and throw down other alley pins.

In witness whereof, I have hereunto affixed my signature in the presence of the witnesses herein named.

WILLIAM M. GENTLE.
